(57) **CLAIM**

(21) Appl. No.: **29/145,480**

The ornamental design for an icon for a portion of a display screen, as shown and described.

(22) Filed: **Jul. 25, 2001**

DESCRIPTION

(51) LOC (7) Cl. **14-02**

The single FIGURE is a front view of an icon for a portion of a display screen. The broken line drawing of a portion of a display screen is for illustrative purposes only and forms no part of the claimed design.
